Patented Feb. 6, 1912.

FIG. 1.

FIG. 2.

INVENTOR

WITNESSES

Franklin S. Smith
BY Cyrus K. Duderison

ATTORNEY

UNITED STATES PATENT OFFICE.

FRANKLIN S. SMITH, OF PHILADELPHIA, PENNSYLVANIA.

ELECTRICAL APPARATUS FOR DESTROYING INSECTS.

1,016,453.

Specification of Letters Patent.

Patented Feb. 6, 1912.

Application filed March 13, 1911. Serial No. 614,183.

To all whom it may concern:

Be it known that I, FRANKLIN S. SMITH, a citizen of the United States, residing in Philadelphia, county of Philadelphia, State 5 of Pennsylvania, have invented certain new and useful Improvements in Electrical Apparatus for Destroying Insects, of which the following is a specification.

My invention relates to improvements in 10 electrical apparatus for the treatment of articles for the purpose of destroying such insects, their eggs, larvæ or pupæ, as may infest or be present in such articles and it has for its object to provide an apparatus 15 having a relatively large number of oppositely disposed terminals between which terminals electrical discharges successively take place.

A further object of my invention is to 20 provide an apparatus of this character which is composed of a relatively small number of parts and which may be cheaply and economically constructed.

Other objects of my invention will appear 25 from the detailed description thereof (which follows) in connection with the drawings or will be apparent to those skilled in the art to which it relates.

My invention comprehends the combination 30 and arrangement of parts shown in the accompanying drawings which illustrate one convenient form of embodiment of my invention, but it will be understood that changes in the construction and arrangement 35 of the parts may be made within the scope of the claims without departing from my invention.

In the drawings:—Figure 1 is a view 40 showing an end elevation of certain parts entering into the construction of my apparatus, certain other of the parts being shown symbolically and conventionally; and Fig. 2 is a top plan view of certain parts of the apparatus embodying my invention.

Referring to the drawings:—1 designates 45 a source of alternating electric current; 2 designates a variable resistance; and 3 a switch in the circuit 4 which includes the 50 primary coil of a step-up transformer 5.

6 designates a condenser which is in multiple with the secondary coil of the step-up transformer 5. The spark gap 7 of known construction is in series with the condenser 55 and the primary coil 8 of the Tesla coil 9. The rotary member 10 of the spark gap is ro-

tated by means of the motor 11, the said motor also performing an additional function to which reference will be made hereinafter. The opposite ends of the secondary 60 coil of the Tesla coil 9 are connected to the ends of conducting members, such as wires, 15 and 16, which extend spirally around the revoluble cylinders 17 and 18 of insulating material. The said wires 15 and 16 are 65 connected to members 19 and 20 of conducting material which are located short distances apart and arranged spirally, as shown in the drawings, and which project above the surfaces of the cylinders 17 and 70 18. The wires 15 and 16 and the projecting members 19 and 20 do not extend entirely around the cylinders 17 and 18, the circumferential distances between the first and the last of said projecting members on 75 each of said cylinders being equal to the circumferential distance or pitch between the said projections 19 and 20 on the cylinders 17 and 18.

For the purpose of causing revolution of 80 the cylinders 17 and 18, the shaft 25 of the motor 11 is provided with a pinion 26 which engages a gear 27 upon a shaft 28, having a bevel pinion 29 in engagement with a bevel gear 30 upon one end of a shaft 32, the opposite end of which is provided with a bevel gear 32 which engages a bevel gear having 85 connection with the cylinder 18. A shaft 35 of insulating material is connected to the bevel gear 32 and is provided at one end 90 with a bevel gear 36 which engages a bevel gear 37 connected to the cylinder 17. Rotation of the shafts 31 and 35 causes rotation of the bevel gear 32 and 36 which in turn causes synchronous rotation of the cylinders 95 17 and 18. As illustrated, the shafts 31 and 35 are not integral but if desired the said shafts may be constructed integrally of insulating material. It is necessary that the shaft extending between the cylinders 17 100 and 18 should be of insulating material.

40 designates a member of suitable insulating material which supports two series or groups of plugs or members of conducting material 41 and 42, which may be termed 105 contact members and which are located in such position that the projecting members 19 and 20 contact successively therewith or pass thereby in such relation thereto that the current will pass successively from the 110 said projections to the said plugs or members 41 and 42. The members 41 and 42

respectively are connected with conductors which extend to and have connection with terminals arranged in oppositely disposed groups 45 and 46. The said terminals are supported in members 47 and 48 of any suitable insulating material which members are in turn supported upon the upright members 49.

- 50 designates a conveyer of any suitable 10 non-conducting material such as fabric. Only a portion of the said conveyer is shown. The said conveyer is supported in any suitable way and may be driven in any suitable manner and by suitable mechanism 15 so as to convey the material or articles which it is desired to subject to the action of the electrical discharges between the terminals 45 and 46. These discharges take place successively between oppositely disposed terminals and in such order that all parts of 20 the articles or objects being treated will be subjected to their action.

By the word or term "terminal" employed herein, I intend to include any devices or points between which electrical discharges take place.

The broad subject matter of invention disclosed herein and not claimed, is claimed in my co-pending applications, respectively 30 filed January 7th, 1911, Serial No. 601,283, and March 13th, 1911, Serial No. 614,181.

Having thus described my invention, I claim:—

1. In an apparatus of the character described, the combination of a source of electrical energy, groups of oppositely disposed terminals, means for successively connecting the said terminals in the said groups with the said source of electrical energy, and 35 means for supporting articles between the said groups of terminals whereby they may be subjected to the action of the electrical discharges between the said terminals.

2. In an apparatus of the character described, the combination of a source of electrical energy, groups of oppositely disposed terminals, means for successively connecting the terminals in the respective groups with the said source of electrical energy, and 40 means consisting of insulating material for supporting articles between the said groups of terminals, whereby the said articles may be subjected to the action of the electrical discharges between the said terminals.

55 3. In an apparatus of the character described, the combination of a source of elec-

trical energy, a plurality of terminals arranged in oppositely disposed groups, the said terminals being supported by members of insulating material, synchronously rotating members having projections thereon spirally arranged around the said cylinders and being connected together by means of an electric conductor, contact members interposed between the said cylinders and the 60 said terminals and having connection with the said terminals, the said projections on the said cylinders successively contacting with or being brought successively in proximity to the said contact members, and means 65 for connecting the said projections on the said cylinders to the source of electrical energy.

4. In an apparatus of the character described, the combination of a source of alternating electric current, synchronously rotating cylinders each having a conducting member extending spirally partially around the same, the said conducting members being provided with projections at frequent 70 intervals, means for connecting the said conducting members to the said source of alternating electric current, terminals arranged in oppositely disposed groups, and means for successively operatively connecting the 75 said terminals to the said projections.

5. In an apparatus of the character described, the combination of a source of alternating electric current, rotatable cylinders, conducting members extending part way 80 around the said cylinders, projections of conducting material connected at intervals to the said conducting members, the circumferential distance between the first and the last of the said projections upon the respective conducting members being equal to the circumferential distance between any other two adjacent projections, terminals arranged in oppositely disposed groups, said 85 terminals being insulated from each other, the said projections being brought successively into operative relation to the respective terminals of the groups, and insulating means for supporting articles between the 90 said groups of terminals.

In testimony that I claim the foregoing as my invention, I have hereunto signed my name this 11th day of March, A. D. 1911.

FRANKLIN S. SMITH.

In the presence of—

CARRIE E. KLEINFELDER,
CYRUS N. ANDERSON.
